UNITED STATES PATENT OFFICE.

JOSIAH MASON, OF BIRMINGHAM, ENGLAND.

IMPROVEMENT IN PENS.

Specification forming part of Letters Patent No. **152,141**, dated June 16, 1874; application filed April 30, 1874.

To all whom it may concern:

Be it known that I, JOSIAH MASON, of Birmingham, in the county of Warwick, England, have invented a new and useful Improvement in Pens; and I do hereby declare the following to be a full, clear, and exact description thereof, which will enable those skilled in the art to make and use the same, reference being had to the accompanying drawing forming part of this specification, in which drawing—

Figure 1 represents a front view of one of my pens. Figs. 2, 3, 4, and 5, respectively, are modifications of the same.

Similar letters indicate corresponding parts.

This invention relates to certain improvements in metallic pens; and consists in the arrangement, upon the nibs of the pen and at a short distance from the point, of side cheeks or enlargements, for the purpose of arresting the flow of ink on such sides and on the external surfaces of the pen, the ink being supplied to the point of the pen through the slits thereof, in such a manner that a uniform or nearly uniform flow of ink is produced, and the danger of blotting by reason of an overcharged pen is averted.

In the drawing, the letter A designates a slip metallic pen constructed according to my invention. *a a* are its nibs or tips, the outer sides of which are expanded or enlarged, so as to form cheeks or scallops *b b*. These nib-cheeks or enlargements are at a short distance from the point of the pen, and may have the semicircular form here represented, or any other chosen form or shape. The extreme points of the nibs *a a*—that is, the sides thereof beyond the cheeks *b b*—may either be parallel or slightly inclined to one another. When the pen is dipped into ink it is principally retained above the nib-cheeks *b b*, whereby the flow or supply of ink to the point of the pen is made dependent upon the central and auxiliary slits thereof, leaving the external surfaces of the nibs comparatively clear, so that the danger of blotting during writing is to the greatest possible extent averted.

In Figs. 2, 3, 4, and 5 I have shown various

forms or modifications of pens constructed according to my invention. In these pens auxiliary side cheeks *b' b'* are used in combination with the nib-cheeks *b b* just described. These auxiliary cheeks *b' b'* form a part of the slip or shank A of the pen. In Fig. 5 the nib-cheeks *b b* also form a part of said slip or shank, instead of being on the side of the nibs, as in the other figures—that is, the shank of the pen is prolonged downward to near the point of the nibs, as represented in the drawing. In Figs. 1 and 2 the central slit of the pen passes beyond the nib-cheeks *b b*, opening into an enlarged slit, *c*. In Fig. 3 a hole, *d*, is punched midway between the nib-cheeks *b b*, into which hole the aforesaid slit opens or vanishes. In Fig. 4 the slit vanishes into the nib-cheeks *b b*, and each of these cheeks is provided with a hole, *d*. In Fig. 5 the auxiliary cheeks *b' b'* are each provided with a hole, as shown, the end or nib cheeks remaining unpunched, while the central slit passes beyond the whole series of cheeks.

By the formation of side slits *e e* coincident with the side outline of the nibs *a a*, said nibs of the pens, Figs. 2, 3, 4, and 5, are made elastic, and may be made with or without the nib-cheeks *b b*, as the greater portion of the nibs is thus situated between and supported by the auxiliary cheeks *b' b'*, the latter constituting reservoirs for holding the ink, which is fed uniformly to the nibs in writing.

The pens move with great smoothness over the paper, and they are not liable to drop the ink or blot and spirtle the paper, as is common to ordinary steel pens.

These improvements are applicable also to barrel pens.

What I claim as new, and desire to secure by Letters Patent, is—

A metallic pen constructed with one or more pairs of cheek-nibs, *b' b'*, substantially as described, for the purpose described.

JOSIAH MASON.
